FINNED HEAT EXCHANGER

Wallace C. Johnson, Hamden, Conn., assignor to Olin Mathieson Chemical Corporation, East Alton, Ill., a corporation of Virginia

Filed Apr. 12, 1960, Ser. No. 21,690

8 Claims. (Cl. 29—157.3)

This invention relates to hollow sheet metal articles and more particularly to a method of manufacturing hollow articles, such as heat exchangers and the like, of sheet metal having integral fins extending externally therefrom.

In the fabrication of hollow articles such as refrigerator panels, condensers and the like of sheet metal, it is desirable that such structures be provided with external fins for facilitating the transmission or dissipation of heat. Such heat transfer fins are usually brazed or soldered on the structure posing a difficult manufacture problem particularly where an article is of flat or oblong sheet metal, thin walled tubing. This involves not only a complicated and time consuming operation, but in addition is an expensive procedure which frequently fails to result in a rigid and efficient joint between the elements. Such a procedure or operation is further complicated by the need for making good contact between the tube sheet and the fins for proper heat conduction as well as securely assembling the parts. Despite precautions taken for the efficiency and operation of the resultant product, the brazed or soldered joint is, nevertheless, of reduced heat exchange efficiency for lack of unimpeded heat transfer through the joint.

Accordingly, it is an object of this invention to provide a novel process for the manufacture of finned heat exchangers eliminating disadvantages of the prior art.

Another object of this invention is to provide a novel method for the manufacture of a heat exchanger having an extended heat transfer surface.

A still another object of this invention is to provide a novel method for the manufacture of finned heat exchangers.

A further object of this invention is to provide a novel method for the manufacture of thin walled relatively flat metal tube sheet having a plurality of integral fins extending from an external surface of the tube sheet.

A still further object of this invention is to provide a novel method for a substantially simultaneous manufacture of a plurality of said structures having an extended heat transfer surface.

Other objects and advantages will become more apparent from the following description and drawings in which:

FIGURE 1 is a perspective view partly in section illustrating one embodiment of this invention and depicting a plurality of elements in superposed relationship to each other;

FIGURE 2 is an exaggerated cross-sectional view depicting the elements of FIGURE 1 after superimposition upon each other in accordance with one embodiment of this invention;

FIGURE 3 is a partial view in perspective of one of the elements employed in the preceding figures;

FIGURE 4 is a partial view illustrating cross-section of the embodiments of FIGURE 1 upon unification of the various elements illustrated in FIGURES 1 and 2;

FIGURE 5 is a partial view of a cross-section of the embodiments of the preceding figures in a subsequent operation;

FIGURE 6 is a partial cross-sectional view depicting an assembly of elements for illustrating another embodiment of this invention;

FIGURE 9 is a partial cross-sectional view illustrating the structure of FIGURE 8 after a still further operational step;

FIGURE 10 is an exploded view in perspective illustrating a variation for some of the elements that may be employed in the assembly of the embodiment depicted in FIGURE 6; and

FIGURE 11 is a partial view in perspective illustrating the elements of FIGURE 10 after unification to each other.

Broadly, in accordance with this invention a plurality of fin strips are arranged and assembled in spatial relationship with each other between two adjacent panels whose interiors are partially laminated in a pattern of an inflatable system of passageways, or between other similar panel structures, as for example prior to their fabrication from superposed sheets with stop-weld material disposed between them in a pattern defining the desired system of tubular passages. These fin strips are disposed in two layers between the pair of adjacent superposed panels with the strips in each of the layers being arranged in spaced and parallel relationship with each other in their respective layers and with the strips in each of the layers being in staggered and overlapping relationship with the strips in the other of said layers. Prior to assembly the strips are coated with a weld-inhibiting or stop-weld material, such as graphite in water glass, in the portions thereof which are to form the desired fin portions, and to thus separate them from each other and from adjacent panels. Generally, this coating of stop-weld material will be applied to all the surfaces of said strips except in the portions of these strips defined between adjacent edges of adjacent strips overlapping thereon.

After assembly the various elements may be suitably secured together, as by spot-welding, to prevent relative movement between them and then subjected to a pressure reduction, as by pressure welding between a pair of mill rolls, to unify all adjacent surfaces of the elements not separated by the stop-weld material in accordance with conventional practices. Typical conditions with which the panel of this invention is unified or welded are set forth in the well known process of fabricating hollow panels, such as refrigerator heat exchangers and the like, disclosed in the patent to Grenell, U.S. No. 2,690,002, granted on September 28, 1954.

Upon unification of the various elements the strips in one layer become unified or integrated to one of the panels adjacent the opposite layer, of strips, with the unwelded portion of the strips being in interlocked relation with each other. The adjacent panels are then separated, such as by spacing them from each other sufficiently to disengage the overlapping or interlocked unwelded portions of the strips while forcing these strips to bend away from panel surfaces to which they have welded. Thus, each strip forms a dual fin structure welded to the panel and extending outwardly at an angle therefrom. Separation of the panel may be accomplished by any conventional means, either mechanical or by fluid pressure, whereafter the inflatable laminations within each panel may then be inflated into a panel containing the desired tubular configuration.

In accordance with one aspect of this invention the fins may extend from only one side of the panel by limiting the number of panels in their superposed relationship to two with the assemblage of fin strips adjacent only one side of each panel. In another aspect of this invention the fins may protrude from both sides of the panel in assemblages of three or more superposed panels

where one or more of the panels has an assemblage of strips adjacent each side thereof. In one arrangement the fins may be disposed in any portion and extend in any direction on the panel, for example in portions of the panel between adjacent passages, however, in a preferred arrangement of fins, the passages carry the fins. This preferred arrangement may be obtained by application of the invention to panels having a system of passages comprised of a plurality of inflatable passages in parallel and spaced relationship to each other with passages in one of the superposed panels disposed in spaced and staggered relationship to similar passages in the adjacent panel over which it is superposed with the assembly of fin strips arranged so that the portion of these strips, in one of the layers, devoid of any coating of stop-weld material will be adjacent and opposite one of the two said panels which is adjacent the other of said layers of strips, and in corresponding areas of this panel opposite the passages.

More specifically by reference to the drawings, one embodiment of this invention comprises a plurality of elongated insert or fin strips 1 and 2 having pressure weldable surfaces which are coated with a stop-weld material 3 in the portion of the strips desired to form the fins on the ultimate article. As illustrated in FIGURE 3 one of the strips 1, which may be identical to strip 2, has all of its surfaces coated with stop-weld 3 so as to leave a band 4 devoid of stop-weld material defining the portion of the strip which will be unified, as by welding, to the heat exchanger on which the desired fins are to be formed.

Subsequent to the coating with stop-weld material the strips are disposed between a pair of superposed hollow metal blanks 5 and 6 which have their interior laminated in a predetermined pattern 7 and 8, respectively, defining an inflatable system of tubular passages. These strips are arranged so that strips 1 will be disposed in spaced relationship with each other in one layer adjacent blank 5 whereas strips 2 will be arranged in spaced relationship with each other adjacent blank 6. In addition, the strips in one layer, as for example strips 1, will be also disposed so that each of the bands of the strips devoid of stop-weld material will be opposite and facing the blank, for example blank 6, adjacent the strips in the other layer, for example the layer containing strips 2. In addition, the strips in each layer, as for example 1, further arranged in staggered and overlapping relationship with the strips in the other layer, as for example strips 2, with each of the strips overlapping the other strips in their portions coated with stop-weld material leaving the band on each strip devoid of stop-weld material free for welding to their respective blanks opposite this band.

One method of obtaining blanks 5 and 6 employed in this embodiment is by the aforementioned patent to Grenell wherein a pattern of stop-weld material is interposed between two metal sheets in a pattern defining a corresponding and desired system of passageways after which the sheets are selectively welded, as by pressure welding between mill rolls, in their adjacent areas not separated by the stop-weld material. Although the pattern of laminations 7 employed may be any simple or complicated inflatable pattern of passages, preferably this pattern of internal laminations 7 is comprised of a plurality of inflatable passages 13 in each blank, as illustrated in blank 5, disposed in parallel and spaced relationship to each other with each parallel passage 13 of one blank, as for example 5, being disposed in parallel and staggered relationship to similar parallel passages 13 in the other blank, as for example 6. Also, the passages 13 of one blank are preferably disposed opposite the band of a respective strip devoid of stop-weld material which strip is in a layer of strips adjacent the other panel.

The strips may be arranged between blanks 5 and 6 by positioning the two layers of strips on one of the blanks, such as 6, in the arrangement above specified and then superimposing the other blank on the arrangement

of strips. In order to facilitate the assembly of blanks and strips for subsequent separation by fluid pressure any convenient configuration of edge bars 9 and 10 are disposed adjacent the peripheral edges of the blanks in a manner, permitting their unification to blanks 5 and 6 as by the absence of stop-weld material on these bars. In order to adapt the assembly to subsequent injection of fluid pressure the seams or interfaces between the edge bars may be suitably welded together. However, if the ultimate separation of the unified assembly of strips and blanks is to be separated by mechanical means, the edge bars 9 and 10 may be coated with a stop-weld material to prevent their welding to any of the blanks or strips with their subsequent removal. However, where the assembly of strips and blanks is to be separated by fluid pressure, this assembly is adapted for such separation by applying a coating of stop-weld material 11 to a portion of one of the edge bars 10 in communicating relationship with a face of one of the strips, either 1 or 2, coated with stop-weld material, as for example, a face 12 indicated in FIGURE 2. This coating 11 of stop-weld material adapts the assembly, after unification, for injection of a fluid pressure internally of the assembly.

Although in this embodiment all the strips 1 and 2 have been illustrated as being of equal width, it is to be understood that the widths may be varied depending on the configurations desired in the fin structure of the heat exchanger either by personal preference or by conditions dictated by the application to which the heat exchanger is to be put. In any event, if desired, after assembly of the components various elements in the manner described above, the assembly is appropriately secured together by any conventional manner as by spot-welding so as to prevent relative movement of the elements in preparation for subsequent unification of the elements together.

Although only a pair of blanks 5 and 6 were employed in this embodiment, it is to be understood that any greater number of blanks may be employed with the aforesaid arrangement of strips inserted between adjacent blanks. Where as in this embodiment only a pair of blanks 5 and 6 are employed the ultimate structure will have fins extending from only one face of the blank. However, where more than two blanks, such as three are used, with the aforesaid arrangement of strips between adjacent panels, as will be understood, the blank or blanks having the above arrangement of strips disposed adjacent each of its opposite faces will have, in the final article, fins extending from both opposite faces thereof. Also, any variety of metals may be employed depending not only on economic considerations but particularly upon the specific applications to which the ultimate panel is to be put. Accordingly, the article of this invention may be made from aluminum alloys, copper alloys, titanium, zirconium, steel or similar alloys. Also the blanks and the strips employed may be of any combination of metals for any desired application. Similarly any stop-weld material capable of preventing unification of the various elements between their adjacent surfaces may be substituted for the specific stop-weld material described above.

Subsequent to securing the various elements together against relative movement between them, the assembly of elements is then ready for unification of the various elements in accordance with conventional practices, for example, the elements may be welded together in their adjacent areas not separated by stop-weld material by pressure welding in accordance with the conditions disclosed in the method of the aforementioned patent to Grenell. In accordance with the method described in this patent the assembly of elements is heated to pressure welding temperatures and immediately rolled between a pair of mill rolls which pressure weld together all adjacent surfaces not separated by the stop-weld material resulting in a substantially complete erasure of

the interfaces between the blanks and the strips by interdispersion of the grains between the adjacent surfaces. The resultant juncture is usually characterized by a tensile strength equal to that of the other seamless regions of the structure. As will be understood, the amount of reduction required to effect pressure welding will vary with the particular combination of metal and the physical properties thereof. Generally, a reduction of the order of 35% or more will accomplish pressure welding of adjacent surfaces not separated by the stop-weld material. However, it will be understood that lower or higher percent reductions may be sufficient or required with different metals and/or different temperatures from room temperature on up.

By reference to the exaggerated drawing of FIGURE 4 it can be seen that the portions of the strips devoid of stop-weld material in one layer became welded, upon pressure welding, to corresponding portions of a blank adjacent the strips in the other layer of said strips becoming intergrated therewith. In contrast, the adjacent surfaces between the various strips and blanks separated by the stop-weld material result in laminations 14 extending in a continuous unbroken lamination 14 coextending between all the unwelded portion between the strips and the blanks, thus, defining parallel rows of fins on each blank interlocked with each other.

After pressure welding the blanks 5 and 6, with their attendant fins unified thereto, are then separated by spacing them in any convenient manner, either mechanically or with fluid pressure, sufficiently to disengage the overlapping and interlocked unwelded portions of the strips whereupon each strip welded to its respective panel becomes disengaged from the strips of the other panel while forcing each other away from their respective panel surfaces. Upon separation each strip forms a dual fin structure welded to its respective panel and extending outwardly at an angle therefrom. Where the panel is to be distended mechanically, as for example, by a vacuum applied on the external surfaces of each blank with subsequent spacing, the edge bars 9 and 10 may be removed either as a result of being unwelded due to an initial coating of stop-weld material on all their surfaces, or these bars may be removed by trimming the edges of the blank followed by separation of the blanks.

However, a preferred method of separation is with fluid pressure either by free expansion or between spaced rigid surfaces. In employing this latter means, the welded assembly of elements is placed between a pair of spaced rigid platens 15 and 16, and a suitable fluid is injected into the unwelded portions between the two adjacent blanks through the portion of one of the bars 10 to which the coating of stop-weld material 11 was applied. Thus, a fluid 17 is injected under sufficient pressure within the welded assembly of elements so as to force the two blanks away from each other against the platens which leaves their external surfaces flat. During such inflation the two layer multiplicity of inserts bonded to their respective blanks are forced to bend and disengage from each other to form the desired configuration of fins extending at an angle from their respective blanks. Subsequent to this inflation operation, the inflated assembly of elements may then be removed from between the platens, the edges of the assembly trimmed to separate the finned blanks into separate and individual structures followed by expansion of the internal pattern of tubular laminations contained within each blank in accordance with conventional practices.

Alternately and preferably the pattern of internal laminations of each blank is expanded prior to trimming while the expanded assembly of elements is disposed between platens 15 and 16. In this alternate manner the fluid 17, under pressure, is then sealed between the blanks 5 and 6, and the platens 15 and 16 spaced further apart a distance equal to the amount of expansion desired, in the internal pattern of laminations, out of the faces of the

blank. Thereafter, the fluid pressure are released and the blank withdrawn from the platens and trimmed along its edges to form individual finned and inflated panels adaptable for use as heat exchangers, such as refrigerator evaporator panels, condensers, radiator structures and the like.

In accordance with another embodiment of this invention and by reference to a specific example, four sheets of 1100 type aluminum alloy, in accordance with the 10 Aluminum Association's standard designations, each 10 inches wide, 12 inches long and 0.125 inch thick were arranged into two superposed adjacent pairs of sheets 18 and 19, each pair 18 and 19 having interposed between a stop-weld material disposed in a pattern corresponding to the desired configuration of tubular passages and comprising bands of stop-weld material 20 corresponding to a plurality of parallel inflatable passages in spaced relationship to each other. This pattern of stop-weld material defining the plurality of parallel passages was, as in the 20 previous embodiment, arranged so that the bands 20 of stop-weld material between one pair of sheets 18 and 19 were in parallel and staggered relationship to the bands 20 of stop-weld material disposed between the other pair of sheets 18 and 19.

As illustrated in FIGURE 6, the two pairs of sheets are disposed so that sheets 18 are in the interior of the four sheet pack. Arranged between the two sheets 18, of the two pairs, is an arrangement of insert or fin strips disposed in two layers therebetween, with each layer comprised of relatively wide strips 21 with each adjacent pair interspersed with relatively narrower strips 22. Strips 21 in each layer are arranged in parallel and overlapping relationship with strips 21 of the other layer of strips with all adjacent surfaces between strips 21, of both layers, and the surfaces of the internal sheets 18 adjacent to them separated with stop-weld material 23. This arrangement places the strips 21 in each layer of strips in spaced relationship to each other with the strips 22 disposed between adjacent strips 21 in each layer. These strips 22 are also adjacent the portions 24 of strips 21 in the other layer which are not overlapped by other strips 21 and which are also devoid of stop-weld material. Thus, all surfaces which are adjacent to strips 22 are not separated by any stop-weld material, for example the adjacent and 45 opposing surfaces of inner sheet 18 and the portion 24 of the surface of strip 21 not coated with stop-weld material.

In forming the above assembly each pair of sheets 18 and 19 with the pattern of stop-weld material can be suitably secured to each other by any suitable manner, such as by spot-welding at the corners, to prevent relative movement between them during assembly of the above arrangement of strips 21 and 22 into their respective layers. Subsequent thereto layer of strips formed alternately of strips 21 and 22 are layed on top of one of the pairs of sheets 18 and 19 with strips 21 disposed parallel with and between the portions of the pair of sheets opposite the bands of stop-weld 20, contained between this pair of sheets 18 and 19. Strips 22 are then placed between adjacent strips 21 and disposed so as to be parallel with and over the bands of stop-weld 20, contained between this pair of sheets 18 and 19. A similar and second layer of strips 22 arranged alternately with each other are placed on top of the first layer in parallel relationship therewith. The arrangement of strips 21 in the second layer is such that they are in staggered and overlapping relationship with strips 21 in the first layer. In order to fill the unlapped portion at the most lateral strips 21, an edge or side bar 25 is employed to hold the double layer of strips in closed contact with each other. In the specific example, each of the strips 21 was of the above referred-to 1100 type aluminum alloy twelve inches long, one inch wide and 0.060 inch in thickness, and each of strips 22 was the same alloy, length and thickness but 75 differing in that they were $\frac{1}{4}$ inch wide corresponding to

the width of the portions of strips 21 not overlapped by adjacent strips 21 in the other layer.

Subsequent to the arrangement of strips, the other pair of sheets 18 and 19, with the pattern 20 of stop-weld material between them and secured against relative movement, was then superimposed on the above arrangement of strips 21 and 22 to form a six-ply or sheet pack ten inches wide, twelve inches long and about 0.625 inch in thickness. The interposition of stop-weld material between all adjacent surfaces, of strips 21, and the adjacent surfaces of inner-sheets 18 adjacent them were obtained by coating strips 21, prior to their arrangement in the structure, with a stop-weld material so as to fully cover all their surfaces except one face which is partially covered with stop-weld material so as to leave an uncoated area $\frac{1}{4}$ inch wide down the center of the strip on top of which is placed the narrow $\frac{1}{4}$ inch wide insert having no portion of its surfaces coated with stop-weld material.

After assembly of the six-ply or sheet pack, it was suitably welded at convenient intervals to prevent relative movement between them and the pack was then heated for forty-five minutes at 1000° F. followed by hot rolling it between a pair of mill rolls to a 65% reduction, in two passes, resulting in an elongated structure of 0.220 inch in thickness. This was followed by a cold reduction of 30% so as to obtain a finish gauge in the structure of 0.150 inch.

As will be noted in FIGURE 7, upon pressure welding the adjacent surfaces, strips 22 of each layer are welded to corresponding portions of sheets 18 and to the adjacent uncoated portions of strip 21 in the other layer whereas each pair of adjacent sheets 18 and 19 are welded together in the areas not separated by the patterns of a stop-weld material. The portions within the pressure welded structure prevented from welding by the stop-weld material comprised a system of internal laminations corresponding to the patterns of stop-weld material interposed between each pair of adjacent sheets 18 and 19, to provide an inflatable system of tubular passages including a plurality of inflatable tubular passages 27. In addition, the coating of stop-weld material employed with strips 21 forms a continuous and unbroken lamination defining the division between an interlocked arrangement of the fins welded or unified to each pair of integrated sheets 18 and 19.

Subsequent to the cold reduction the pressure unified assembly at final gauge was placed between a pair of rigid platens 29 and 30 spaced one inch apart. A fluid 31 under a pressure of 500 p.s.i. was then injected into the laminations 28, defined between the unwelded interior portions of the structure defined between the inner-sheets 18 to expand and separate the pairs of unified sheets 18 and 19 away from each other and against the rigid platen adjacent their external faces. During separation these two layers of multiple inserts which were welded, in accordance with the above, alternately to the inner surfaces of the two pairs of unified sheets 18 and 19, were forced to expand, in contact with each other to an elevated position of 45° with the edges passing, although not shown, beyond contact with each other forming. This separation of the panels 34 and 35 with its attendant unlocking of the interwoven fins, welded to their respective panels, spatially forms the strips into a corresponding arrangement of fins 36 and 37 welded to panels 34 and 35 respectively.

Subsequently, the pressure was then sealed between the pressure unified sheets 18 and 19 and the rigid platens 29 and 30 spaced slightly further apart a distance equal to the expansion desired in the inflatable system of tubular passages. Thereafter, a fluid 32 under sufficient pressure was injected into the system of inflatable tubular passages to expand them into contact against the rigid platens 29 and 30 adjacent each external face of the structure. This expansion formed the corresponding system of tubular passages including a plurality of parallel

spaced passages 33 in each panel on which the fins were formed. During expansion, which involves elongation of the metal defining the tubular passages, the structure is restrained on its outer surfaces by the rigid platens, and restrained on the inner finned surface by the original 5 inflating fluid employed for separating the panels and which is sealed between them. Upon completion of the expansion the fluid pressure is released and the water drained from within the expanded structure which is then removed from between the platens. Thereafter, the edges 10 of the inflated structure were trimmed as along line 38 to allow the panels to be removed from each other into separate and individual panels with their respective fins welded thereon. In accordance with this specific example in this embodiment, the fin structure had a 0.015 15 inch thickness corresponding to a tubular wall thickness, inflated, of 0.060 inch in thickness which is about one-half the thickness of the tubular wall. As will be understood the fins can be made thinner or thicker as desired in accordance with the requirements of various 20 applications.

In a variation of this embodiment FIGURES 10 and 11 illustrate a manner in which the fin strips 22 of one layer may be unified to a strip 21 prior to placement in the arrangement between adjacent pairs of sheets 18 and 25 19. As illustrated in FIGURE 10, strip 22 may be superimposed on strip 21 and the two strips suitably secured or unified together to form a combined strip 39, by spot-welding or pressure welding. This strip 39 30 is then coated with stop-weld material 41 on all surfaces, except on the face 40 of strip 22 opposite the face welded on strip 21, prior to its placement in the arrangement of strips disposed between the two adjacent pairs of sheets 18 and 19.

35 In addition, although a simple internally laminated panel has been described, it is to be also understood that the invention is equally applicable to sheets having other patterns of internal laminations either in the single stratum or plural strata, or in other configurations, as for example the panel disclosed in the patent to Adams, U.S. 2,766,514, granted on October 16, 1956.

Although the invention has been described with reference to specific embodiments, materials and details, various modifications and changes, within the scope of this 45 invention, will be apparent to one skilled in the art, and are contemplated to be embraced within the invention.

What is claimed is:

1. A method for making hollow panels with integral fins extending therefrom with each of said panels being ductile and having internally disposed therein an unjoined interior portion extending in a pattern defining a desired system of tubular passages adapted to contain a fluid, said method comprising superposing said panels on each other with a plurality of parallel and ductile fin strips disposed in two layers between two adjacent panels and with each of said strips separated from each other and from said adjacent panels by a stratum of stop-weld material disposed adjacent the portions of said strips desired to form said fins, said strips in each of said layers being 50 arranged in spaced relationship with each other in their respective layers and with said strips in one of said layers arranged in staggered and overlapping relationship with said strips in the other of said layers, and said stratum comprising areas devoid of said stop-weld material between the surfaces of each of said strips and the surfaces of said two panels in the portions of said strips defined between adjacent edges of adjacent strips overlapping thereon; pressure welding the assembly of said panels and said strips in their adjacent areas not separated by said stop-weld material whereby the strips in each one of said layers are welded to corresponding portions of one of said two panels adjacent the strips in the other of said layers; and separating said panels by spacing them from each other sufficiently to disengage the overlapping unwelded portions of said strips whereby 55
- 60
- 65
- 70
- 75

each of said layers of strips welded to one of said two panels forces the strips of the other of said layers from their respective panels at an angle therefrom to form said fins.

2. A method for making hollow panels with integral fins extending therefrom with each of said panels being ductile and having internally disposed therein an unjoined interior portion extending in a pattern defining a desired system of tubular passages adapted to contain a fluid and comprised of a plurality of said passages disposed in parallel and spaced relationship to each other, said method comprising superposing said panels on each other with a plurality of parallel and ductile fin strips disposed in two layers between two adjacent panels and with each of said strips separated from each other and from said two panels by a stratum of stop-weld material disposed adjacent the portions of said strips desired to form said fins, said plurality of passages of one of said two panels being disposed in parallel and staggered relationship to said plurality of passages in the other of said two panels, and said strips in each of said layers being arranged in spaced relationship with each other in their respective layers with said strips in each of said layers arranged in staggered and overlapping relationship with said strips in the other of said layers, and said stratum comprising areas devoid of said stop-weld material between the surfaces of each of said strips and the surfaces of said two panels in the portions of said strips defined between adjacent edges of adjacent strips overlapping thereon with said areas of said strips in each of said layers opposite the portion of said stratum devoid of said stop-weld material being adjacent and opposite one of said two panels adjacent the other of said layers in corresponding areas of said one panel opposite said plurality of passages; pressure welding the assembly of said panel and strips in their adjacent areas not separated by said stop-weld material whereby the strips in each of said layers are welded to corresponding portions of one of said two panels adjacent the strips in the other of said layers; and separating said panels by spacing them from each other sufficiently to disengage the overlapping unwelded portions of said strips whereby one of said layers of strips welded to one of said two panels forces the strips of the other of said layers from their respective panels at an angle therefrom to form said fins.

3. A method for making hollow panels with integral fins extending therefrom with each of said panels having internally disposed therein an unjoined interior portion extending in a pattern defining a desired system of tubular passages adapted to contain a fluid, said method comprising forming a structure of a plurality of superposed metal sheets from at least a pair of adjacent first sheets and a second sheet adjacent the external face of each of first sheets, a plurality of parallel and ductile fin strips disposed in two layers between said first sheets with a stratum of stop-weld material separating adjacent surfaces of said first and second sheets and said strips, said stop-weld material being disposed between adjacent first and second sheets in a pattern corresponding to a desired system of tubular passages and disposed adjacent the portions of said strips desired to form said fins, and said strips in each of said layers being arranged in spaced relationship with each other in their respective layers with said strips in one of said layers arranged in staggered and overlapping relationship with said strips in the other of said layers wherein a stratum stop-weld material adjacent said strips comprising areas devoid of said material between the surfaces of each of said strips in the portions of said strips defined between adjacent edges of the strips overlapping thereon; pressure welding the assembly of said sheets and said strips in their adjacent areas not separated by said stop-weld material whereby adjacent first and second sheets form said panels and said strips in each of said layers are welded to corresponding portions of one of said first sheets adjacent the strips in the other of said

layers; and separating said panels by spacing them from each other sufficiently to disengage the overlapping unwelded portions of said strips whereby one of said layers of strips welded to one of said first panels forces the strips of the other of said layers from their respective panels at an angle therefrom to form said fins.

4. The method of claim 3 wherein said pattern of stop-weld material comprises a plurality of said passages disposed in parallel and spaced relationship to each other with said plurality of passages between one of said first sheets and the second sheet adjacent thereto are disposed in parallel and staggered relationship to said plurality of passages between the other of said first sheets and the second sheet adjacent thereto, and said areas devoid of said material arranged opposite one of said first sheets adjacent the other of said layers in corresponding areas of said one first sheet opposite said plurality of passages.

5. A method for making hollow panels with integral fins extending therefrom with each of said panels being ductile and having internally disposed therein an unjoined interior portion extending in a pattern defining a desired system of tubular passages adapted to contain a fluid, said method comprising superposing said panels on each other with a plurality of parallel and ductile fin strips disposed between two adjacent panels with said strips in each of said layers comprising a plurality of first fin strips and a plurality of second fin strips and said first strips in both said layers being separated from each other and from said two panels by a stratum of stop-weld material, said first strips in each of said layers being arranged in spaced relationship with each other in their respective layers and in staggered and overlapping relationship with said first strips in the other of said layers with said second strips being disposed in portions of each of said layers between adjacent first strips therein and adjacent a first strip in the other of said layers overlapped by said adjacent first strips and with the said stratum in said portions comprising areas devoid of said stop-weld material; pressure welding the assembly of said panels and said strips in their adjacent areas not separated by said stop-weld material whereby said first strips in each of said layers are welded to one of said two panels adjacent thereto and to a second strip adjacent thereto in the other of said layers; and separating said panels by spacing them from each other sufficiently to disengage the overlapping unwelded portions of said second strips whereby the portion of said strips welded to one of said two panels disengages from and forces the other of said strips welded to the other of said panels away from their respective panels to form said fins.

6. The method of claim 5 wherein said system of tubular passages is comprised of a plurality of said passages disposed in parallel and spaced relationship to each other with said plurality of passages in one of said two panels disposed in parallel and staggered relationship to said plurality of passages of the other of said two panels, and said second strips being arranged opposite corresponding areas of one of said panels adjacent thereto opposite said plurality of passages.

7. A method for making hollow panels with integral fins extending therefrom with each of said panels having internally disposed therein an unjoined interior portion extending in a pattern defining a desired system of tubular passages adapted to contain a fluid, said method comprising forming a structure of a plurality of ductile metal sheets from at least a pair of adjacent first sheets and a second sheet adjacent the external face of each of said first sheets, a plurality of parallel and ductile fin strips disposed in the two layers between said first sheets with said strips in each of said layers comprised of a plurality of first fin strips and a plurality of second fin strips, and a stratum of stop-weld material separating adjacent surfaces of said first sheets, second sheets and said first strips with said stop-weld material being disposed between adjacent first and second sheets with a pattern corresponding

to desired system of tubular passages and disposed between each of said first strips and said first sheets adjacent the portions of first strips desired to form said fins, and said first strips in each of said layers being arranged in spaced relationship with each other in their respective layers and in staggered and overlapping relationship with said first strips in the other of said layers with said second strips disposed in portions of each of said layers between adjacent first strips therein and adjacent a first strip in the other of said layers overlapped by adjacent first strips and with said stratum in said portions comprising areas devoid of said stop-weld material; pressure welding the assembly of said sheets and said strips in their adjacent areas not separated by said stop-weld material whereby adjacent first and second sheets form said panels and said second strips in each of said layers are welded to corresponding portions of one of said first sheets and to a second strip adjacent thereto in the other of said layers; and separating said panels by spacing them from each other sufficiently to disengage the overlapping unwelded portions of said second strips whereby the portion of said

strips welded to one of said two panels disengages from and forces the other of said strips welded to the other of said panels away from their respective panels to form said fins.

8. The method of claim 7 wherein said system of tubular passages is comprised of a plurality of said passages disposed in parallel and spaced relationship to each other with said plurality of passages in one of said two panels disposed in parallel and staggered relationship to said plurality of passages of the other of said two panels, and said second strip being arranged opposite corresponding areas of one of said panels adjacent thereto opposite said plurality of passages.
